CLAIM

The ornamental design for a sport shoe, as shown and described.

DESCRIPTION

FIG. 1 is a top and right front perspective view of a sport shoe showing my new design;

FIG. 2 is a left side elevational view thereof;

FIG. 3 is a rear elevational view thereof;

FIG. 4 is a top plan view thereof;

FIG. 5 is a top and right front perspective view of another embodiment of my new design of FIGS. 1-4;

FIG. 6 is a left side elevational view thereof;

FIG. 7 is a rear elevational view thereof; and

FIG. 8 is a top plan view thereof.

The sole pattern is a continuation of that shown by FIGS. 3 and 7.
